UNITED STATES PATENT OFFICE

PETER J. STEINBACH, OF CHICAGO, ILLINOIS.

SEAT SPRING.

1,410,039.

Specification of Letters Patent. Patented Mar. 21, 1922.

Application filed September 29, 1921. Serial No. 504,225.

To all whom it may concern:

Be it known that I, PETER J. STEINBACH, a citizen of the United States, residing at Chicago, in the county of Cook and State of Illinois, have invented certain new and useful Improvements in Seat Springs, of which the following is a specification.

This invention relates to seat springs of the kind commonly employed for the seats of 10 automobiles, and the main object of the invention is to provide an improved seat spring of this character characterized by increased durability, comfortable riding qualities, and freedom from liability to distortion and deformation from use.

Other objects of the invention are, to provide a seat spring of the multiple coil spring type which shall permit the use of the maximum number of springs in a given seat area; 20 to provide a seat spring of this type which shall afford substantially uniform and equal elastic resistance to pressure throughout its entire upper surface; to provide in a seat spring an improved base with improved 25 means for anchoring the lower ends of the coil springs thereto; to provide, in a seat spring, an improved means for bonding the upper ends of the coil springs to each other and to the top marginal frame of the spring; 30 to provide, in a seat spring, an improved means for anchoring the sides of the top frame of the spring to the base so as to prevent lateral sagging or displacement of the upper portion of the spring without interfering with the action of the coils; and, in 35 general, to provide a simple and inexpensive seat spring readily adapted to cooperate with the usual cloth or leather covering and upper seat pad and to produce a minimum of 40 wear on the latter in use.

Other objects and attendant advantages of the invention will be apparent to persons skilled in this art from the following detailed description, taken in connection with 45 the accompanying drawings, wherein I have illustrated a practical and approved form of the invention as embodied in a square spring for an individual seat, and in which:

Fig. 1 is a top plan view partly in horizontal section showing my improved seat spring;

Fig. 2 is a side elevation;

Fig. 3 is a fragmentary detail showing the method of anchoring the lower ends of the 55 guy chains.

Referring to the drawing, 5 designates a

rectangular base plate of sheet metal, from which are cut and struck upwardly a plurality of groups of tongues 6 and 7. The tongues of each of these groups as herein shown are four in number disposed ninety degrees apart around a common center which coincides with the vertical axis of one of the springs hereinafter described. These groups of tongues are arranged in alternating order 65 in intersecting rows lying at right angles to each other. 8 and 9 designate conical coil springs, the springs 8 resting at their wide ends on the base 5 and the springs 9 being relatively inverted and resting at their narrow ends on the base 5. The springs 8 and 9 are likewise arranged in alternating relation 70 in intersecting rows disposed at right angles to each other. The wide lowermost coil of each of the springs 8 is securely anchored to 75 the base plate 5 by means of the tongues 6 which are bent outwardly and downwardly to overlie the same; and the narrow lowermost coils of the springs 9 are likewise anchored to the base plate 5 by the tongues 7. 80 By reason of this relative inversion of adjacent springs in each of the rows of the two intersecting series, it is possible to dispose the springs in very close and compact relation with their sides obliquely overlapping 85 each other, and to use, in a structure of a given size, a much larger number of springs than is possible where all of the springs are mounted on the base at either their wide or 90 their narrow ends.

10 designates a top frame member, conveniently formed of a rod bent to the rectangular form shown, with its meeting ends united by a sleeve or ferrule 11, this frame member having substantially the same marginal form and dimensions as the base plate 95 5. Anchored to and extending between opposite sides of the frame 10 are two series of bonding wires 12 and 13 disposed at right angles to each other, one wire of each group 100 crossing the top coil of each spring and anchored to the latter by integral loops 14. In assembling, the bonding wires 12 and 13 first have the loops 14 formed in them by suitable mandrels, and the upper coils of the springs 105 are then threaded through these loops. The ends of the bonding wires 12 and 13 are anchored to the opposite sides of the longitudinal frame 10 as by being coiled around the latter, as shown at 15.

By the use of these bonding wires 12 and 13 the upper ends of the coil springs are ac-

curately spaced and securely held in correct relation to each other; and by means of the fastening tongues 6, the lower ends of the springs are also accurately spaced and rigidly anchored in correct relation. Hence, it is impossible, under the severest conditions of use, for individual springs to break away or yield in any direction independently of the other springs of the set.

10 The structure as thus far described is well suited and adapted to effectuate the main purpose of the invention. But in order to oppose the tendency of the upper portion of the structure to bend laterally relatively to 15 the lower portion, which sometimes occurs in comparatively deep springs of this general type when the load is imposed principally upon the edge of the structure, I anchor the four sides of the top frame 10 to the base 20 plate by guy chains 16, of which, in the present instance two are shown connected to each side of the frame 10 somewhat inwardly from the corners of the latter and extending inwardly and downwardly and anchored at 25 their lower ends to the base plate 5; this anchoring of the guy chains at their lower ends being conveniently effected by means of hooks 17 (Fig. 3) engaged with the margins of the openings from which the tongues 6 30 are struck. Manifestly the guy chains 16 do not interfere at all with the vertical or up and down movements of the springs 8 and 9, but they effectively check any substantial or excessive lateral movement in any 35 direction of the top frame 10, and thus prevent any permanent deformation of the springs in the outer rows. The described structure produces a seat spring of great resiliency and one wherein the cushioning effect is very closely and uniformly distributed 40 throughout the entire area of the seat. The component parts of the structure are united so securely that it is impossible for any part to work loose and get out of place. 45 The structure likewise provides a maximum of strength to resiliently support superimposed weights, while at the same time it is sufficiently light in weight to enable the seat in which it is contained to be handled 50 without appreciable effort. Finally, by reason of the compact grouping of the springs, their strong and rigid connections at top and bottom, and the presence of the guy chains, it is practically impossible for the 55 spring to become locally weak or deformed.

Manifestly, the specific details of structure and arrangement herein shown and described may be considerably modified without involving any departure from the principles or sacrificing any of the advantages of the invention. Hence, I do not limit the latter to the precise structure illustrated, ex-

cept to the extent clearly indicated in the specific claims.

I claim:

1. A seat spring, comprising a rectangular flat sheet metal base-plate, a top frame consisting of a rod bent in rectangular form and of substantially the same marginal dimensions as said base-plate, means for uniting the meeting ends of said rod, conical springs mounted on said base-plate in rows parallel with the edges of the latter, adjacent springs in each row being relatively inverted and in such close juxtaposition that their sides obliquely overlap each other, and means for bonding the upper ends of said springs to each other and to said top frame; said springs being wholly held by said base-plate and said bonding means. 80

2. A seat spring, comprising a rectangular flat sheet metal base-plate, a top frame consisting of a rod bent in rectangular form and of substantially the same marginal dimensions as said base-plate, means for coupling the meeting ends of said rod, conical springs stepped on said base-plate in rows parallel with the edges of the latter, adjacent springs in each row being relatively inverted and in such close juxtaposition that their sides obliquely overlap each other, integral tongues on said base-plate in clamping engagement with the lowermost coils of said springs, and means for bonding the upper ends of said springs to each other and to said top frame; said springs being wholly held by said base-plate and said bonding means. 85

3. In a seat spring of the character described, the combination of a flat base-plate, a group of coil springs mounted on said base-plate, a top frame member of substantially the same dimensions as said base-plate, means for bonding the tops of said springs to each other and to said top frame member, and downwardly and inwardly inclined guy chains connecting the margin of said top frame member to said base-plate inwardly of the margin of the latter. 100

4. In a seat spring of the character described, the combination of a flat rectangular base-plate, a group of coil springs mounted in rectangularly intersecting rows on said base-plate, a top frame consisting of a rod bent in rectangular form and of substantially the same dimensions as said base-plate, bonding wires connecting the top coils of said springs to each other and to the sides of said top frame, and downwardly and inwardly inclined guy chains connecting the 105 sides of said top frame to said base-plate inwardly of the edges of the latter. 115
